Des. 459

Wm Redheffer of Philadelphia Pa
Letters Patent No 459 Dated May 25th 1852.

The schedule referred to in these Letters Patent and making part of the same

To all whom it may concern.

Be it known that Wm Redheffer comb-
maker of the District of Spring Garden in the County of Philadelphia and State of
Pennsylvania have invented or produced a new design or figure, in which fancy
combs can be made from several parts or pieces of Turtle shell, Horn or other ma-
terial, and I do hereby declare that the following is a full and exact description
of the same. This design or figure consists in making fancy combs from several
parts or pieces, by drawing, weaving, twisting or plaiting a ribbon or cord
like piece or pieces of the same or other material through openings on the

back of the comb near the edge forming a series of single or double loops or curvatures around the edge of the comb in form and shape as represented in the accompanying drawings which makes a part of this specification.

Fig 1st Represents a comb drawn, woven, twisted or plaited A the back of the comb B the loops or curvatures C the openings.

Fig 2^d Represents a comb drawn, woven, twisted or plaited with the double loop or curvature A the round and B the flat straw.

What I claim as my invention and wish to secure by Letters Patent is the design and configuration of fancy combs above described and herein set forth.
